CLAIM

The ornamental design for a hat rack, as shown and described.

DESCRIPTION

FIG. 1 is a front perspective view of a hat rack, showing my new design;

FIG. 2 is a rear, bottom perspective view thereof;

FIG. 3 is a front elevational view thereof, the rear elevational view being a mirror image of FIG. 3;

FIG. 4 is a left side view thereof;

FIG. 5 is a right side view thereof;

FIG. 6 is a top plan view thereof;

FIG. 7 is a bottom plan view thereof;

FIG. 8 is an exploded front perspective view of the hat rack; and,

FIG. 9 is an exploded rear, bottom perspective view of the hat rack.

The dashed broken lines in the figures are for the purposes of illustrating portions of the hat rack, which form no part of the claimed design.
